RALPH A. LIGHTT, OF CYNWYD, AND JOSEPH W. PRICE, JR., OF PHILADELPHIA, PENNSYLVANIA, ASSIGNORS TO THE UNITED STATES METALLIC PACKING COMPANY, OF PHILADELPHIA, PENNSYLVANIA, A CORPORATION OF PENNSYLVANIA

AUTOMATIC AIR DISTRIBUTING VALVE FOR SANDER SYSTEMS

Application filed June 23, 1931. Serial No. 546,193.

Our invention relates to sander systems of the general character described in our prior Patent 1,800,548. In this patent we have shown and described a distributing valve adapted to automatically connect the air supply pipe of the system successively with the clean out and air delivery nozzles of the sand trap so that when air pressure is turned into the system a short blast of air will be delivered through the clean out nozzle and then the air is directed into the delivery nozzle of the trap and in our pending application, Serial No. 529,462, filed April 11, 1931, we have described an improved construction of the air distributing valve. The object of our present invention is to provide for certain additional improvements in the distributing valve and sander system by providing a distributing valve, which in normal inoperative position will close all ports leading into and out of the distributing valve casing and which, when pressure air is turned on, will open the admission port into the casing to the passage of pressure air and successively connect this port with the outlet port or ports leading to the clean out nozzles of the trap and then after closing this port or ports, connect the inlet port with a port or ports leading to the sand delivery nozzles of the trap, the prime object of our improvement being that the valve in inoperative position, that is to say, when no pressure air is provided, will close the distributing valve casing to all passages leading to or from it and also to secure a structure which, on the turning on of pressure air to the system, will ensure prompt delivery to the clean out nozzle of the sand trap of a short blast of high pressure air, the beginning and duration of which is controlled by a pneumatic valve actuating mechanism connected to the air supply pipe of the system.

The nature of our improved construction will be best understood as described in connection with the drawings in which it is illustrated and in which

Figure 1 is a diagrammatic showing of a locomotive sander system of the kind to which our invention is applicable.

Figure 2 is a sectional vertical elevation

showing the construction of our improved distributing valve.

Figure 3 is a view similar to Fig. 2 but showing a modification of the valve construction, and

Figure 4 is a cross section on the line 4—4 of Fig. 3.

A indicates the supply pipe through which compressed air from a reservoir, not shown, is conducted to the distributing valve of the sander system, A¹ indicating a control valve usually located in the engineer's cab, for admitting and cutting off the air supply to the pipe A. B indicates the distributing valve receiving air from the pipe A and distributing it in timed relation to the pipes C and D, connected respectively with the clean out nozzle E and sand delivery nozzle F of the sand trap, indicated at G. This trap is of a usual construction, having a sand retaining bowl G¹ supplied with sand from a reservoir, not shown, through the pipe G² and an outlet passage G³ to which is connected the delivery pipe H, which conducts the sand to the trap.

The distributing valve casing and its appurtenances, as shown in Figs. 2 and 3, are practically identical. It consists of a cylindrical casing B closed at top by a head I and at bottom by a head J, which latter head has one or more openings, as indicated at J¹, to permit the free flow of air from and to this portion of the casing. This head J is also provided with a central seat, indicated at J², for a coiled spring, indicated at K. The valve casing is provided with an inlet port indicated at L, which is connected with the supply pipe A of the system and, as shown, has two oppositely located outlet ports L¹, one of which is connected with the pipe C leading to the clean out nozzle E of the sand trap and the other one of which would lead to a similar nozzle in another trap. Spaced from the ports L¹, as shown lower down in the valve casing, is another outlet port indicated at L² which is connected through the pipe D with the sand delivery nozzle F of the trap. As shown, this passage is bifurcated, as indicated at L², so as to be connectable with two traps. M is a passage of restricted area, formed as shown through the wall of the

- casing B^1 and connecting with the passage formed in the casing leading to the inlet port at one end and to the top of the cylinder B^1 at its other end. N is a piston fitting in the cylindrical casing B^1 , the upper portion of which N^1 forms a piston working in connection with the pneumatic cylinder formed by the upper portion of the casing, while the lower portion of this piston, indicated at N^2 , 5 forms a piston valve working in connection with the inlet and outlet ports of the cylindrical casing. The piston N is normally returned to and held in the retracted position shown in Fig. 2 by the action of the spring K , 10 which presses against the bottom of the piston and, as shown in Fig. 2, the valve portion of the piston is provided with a transmission passage for air, which, in this modification, is an annular groove O , so located that when 15 the valve is in retracted position it does not register either with the inlet port L or with any of the outlet ports indicated at L^1 and L^2 . The location and shape of the groove O and the location and shape of the inlet port L , 20 are such that the groove O registers and remains in registry with this port as the valve moves downward and the location of the outlet ports L^1 are such that as the valve moves downward the groove comes first into registry with the ports L^1 connected with the 25 clean out nozzle, then moves downward out of registry with these ports and registers with the port L^2 at the bottom of the downward movement of the piston valve.
- 30 In the modified structure illustrated in Fig. 3, the piston valve is provided with air passages formed through the valve instead of around the valve, as in Fig. 2. These passages are made up of an inlet passage P connected with lateral passages P^1 located to register with the outlet ports L^1 as the valve moves downward and a third passage P^2 located to register with the port L^2 on the further downward movement of the 35 valve. To prevent any rotary movement of the piston valve, the piston valve is longitudinally grooved, as indicated at Q in Figs. 3 and 4, and a screw Q^1 is inserted through the casing so that its end extends into the 40 groove Q .
- In operation it will be observed that when 45 no pressure air is delivered to the system through the pipe A the spring K , acting on the bottom of the piston valve N^2 , will force and hold the valve to the upper position, as indicated in Figs. 2 and 3, the piston N^1 being also moved up in the upper part of the cylindrical valve casing. The spring is enabled to act promptly upon the valve on the 50 cutting off of air pressure because the portion of the cylinder B^1 in which it is located is in free communication with the atmosphere through a port or ports J^1 , so that in moving the valve up it is not opposed by any 55 vacuum in the lower part of the cylindrical 60 casing. When the pressure air is turned into the supply pipe A it passes first through the restricted passage M into the head of the cylinder B^1 and, acting on the piston head N^1 , presses the valve N^2 downward against the action of the spring K , bringing the channel through the valve, which may be either the groove O of Fig. 2 or the passage P of Fig. 3, into registry with the admission port L of the casing. This movement of the valve 65 also brings the groove O of Fig. 2 or the passages P^1 of Fig. 3 into registry with the ports L^1 connected to the clean out nozzles of the sand trap or traps, so that a short blast of air of full head will be delivered to the clean 70 out nozzle. The further movement of the valve first closes the ports L^1 and then brings the groove O or passage P^2 of Fig. 3 into registry with the outlet port L^2 , delivering the full head of pressure air to the delivery 75 nozzle of the trap or traps. When the air is cut off from the supply pipe A the spring K , as already stated, returns the valve to its normal inoperative position, in which it 80 closes all ports leading to or from the valve 85 casing.
- It will be understood that the rapidity with which the valve will be shifted on the turning on of pressure air can be regulated by regulating the area of the restricted passage M and in this way the duration of the short blast to the clean out nozzle is regulated. 90
- Having now described our invention, what we claim as new and desire to secure by Letters Patent, is:
- In a sander system comprising an air supply pipe and a sand trap provided with a clean out nozzle and a delivery nozzle and a distributing valve comprising a casing having an inlet port connected to the supply pipe and spaced outlet ports connected to the clean out and delivery nozzles of the sand trap, a valve movable in said casing in normally inactive position closing the inlet port, said valve being provided with an air channel, which as the valve is shifted in the casing will register with the air inlet port of the casing and successively as the valve continues its movement register with the outlet port connected to the clean out nozzle and then with the outlet port connected to the delivery nozzle, pneumatic valve actuating mechanism operative under air pressure to shift the valve from its normal inoperative position the pneumatic valve actuating mechanism being connected by a restricted passage to receive pressure air from the air supply pipe and resilient means tending to restore and hold the valve in normally inoperative position.
